UNITED STATES PATENT OFFICE.

ALFRED C. DANKS, OF CLEVELAND, OHIO.

BAFFLE FOR STEAM DRUMS.

Application filed June 30, 1927. Serial No. 202,569.

The invention relates to baffle constructions for steam boilers. It is applicable to boilers of all types in which a steam liberating space is provided above the level of the water. Its hangers are preferably constructed entirely of cast iron, in order to withstand the destructive action of the water or agents carried thereby, and the device is built in sections in such manner that the parts are interchangeable, rendering replacement or removal easy. The apparatus is constructed so as to utilize the upper part of the boiler drum as the dry steam chamber, in contrast to other devices which carry the steam chamber as a part of their construction. The invention has for its objects, the provision of a construction embodying the features specified above, wherein: (1) a very durable construction is secured, without any requirement for bolts and nuts, subject to rust or corrosive action; (2) the baffles are self-draining, requiring no outside drainage and consequent loss of heated water and corresponding reduction in efficiency; (3) a very efficient baffling of the wet steam is secured, incident to the tortuous passage required and to the relative arrangement of the baffle plates; (4) the various plates and baffles are effectively sealed, one from the other, to insure against leakage and cause the steam to pass through the slots provided for the purpose; (5) the baffles are all properly drained and the passages shielded against an inflow of water in the reverse direction through such passages, and; (6) a relatively cheap, simple construction is secured, which may be easily assembled and disassembled for the purposes of replacement and repair. One embodiment of the invention is illustrated in the accompanying drawings, wherein:

Figure 1 is a longitudinal section through a drum equipped with the improvement. Fig. 2 is a section through the drum showing the baffles in end elevation. Figs. 3 and 4 are sections through the baffles taken respectively longitudinally of the drum and transversely thereof. Figs. 5, 6 and 7 are detail views of the cover plates used at the ends of the separator, Fig. 5 being a side elevation, Fig. 6 a vertical section, and Fig. 7 a plan view. Figs. 8, 9 and 10 are detail views of one of the sections of the distributing plate located above the baffles, Fig. 8 being a section on the line VIII—VIII of Fig. 9, Fig. 9 being a plan view and Fig. 10

being an end elevation. And Fig. 11 is an enlarged vertical section through one of the hangers and the end of the distributing plate.

Referring to the drawings, 1 is a steam drum having an outlet 2, and provided with a pair of longitudinally extending hangers 3 and 4, preferably of cast iron located on opposite sides of the outlet and secured in position by means of the studs 5. A recess is provided at 6 in each hanger and filled with suitable packing, so that a tight joint is made with the wall of the drum.

Supported on the hangers is a distributing plate made up of the three sections 7, 8 and 9 (Fig. 3). These sections are suitably stiffened by the ribs 10 and are made of cast iron to give the necessary corrosion resisting properties. The sections of the plates are also slotted, as indicated at 11 in Figs. 3 and 9, the slots being of varying length depending on conditions. Beneath the distributing plate and supported therefrom are the four baffles 12, 13, 14 and 15, each of which is also made in a plurality of sections fitting together, as indicated at 16 (Fig. 3). These baffles are, like the hangers, preferably of cast iron, and interfit with each other and with the distributing plate, as indicated at 17 (Fig. 3) and at 18 (Fig. 4) in order to guard against leakage.

The baffle sections 12 just below the sections of the distributing plate, are hung therefrom by the dovetail interlocking connections 19 and 20, as indicated in Fig. 4, and each succeeding baffle section is similarly connected to the one just below by similar connections 19 and 20. In this manner, the baffle sections are releasably supported without the use of bolts or the like. These connections may be easily assembled and disassembled by a sliding longitudinal movement, and being of cast iron, the same as the baffles and hangers, are not subject to corrosion. By this means also, the series of baffles may be increased as desired by adding other sections below the lowest section 15 shown. Each of the baffle sections consists of a series of inverted channels or U's 21 having the slots or perforations 22 through their top walls or webs. Between these channels 21 are the U-shaped drain passages 23 extending to the ends of the sections and preferably discharging through both ends through the slots 24, 24. In order to shield these slots where a circulation pipe

enters the drum, such as the pipe 25 (Fig. 2), the hanger may be provided with an extension 26. In fact, such shields may be used, if desired, throughout the length of the headers in order to shield all of the slots 24, 24 from water splashed or thrown up from the body of water in the drum.

As indicated in Fig. 3, the channels 21 of each section are staggered with respect to the channels 21 of the next section above, so that the steam, in passing up through the series of baffles, via the slots 22, will necessarily pursue the zig-zag path indicated by the arrows in Fig. 3, thus tending to increase the effectiveness of the separation of the steam and water, the water which is deposited on the sections flowing down into the passages 23, and then draining longitudinally of said passages and discharging through the slots 24.

In order to close off the ends of the dry steam chamber 27 (Figs. 1 and 2) above the distributing plate, the segmental plates 28, 28 (Fig. 1), shown in detail in Figs. 5, 6 and 7 are employed. These plates are perforated at 29, and provided with flanges 30 at their upper edges having therein the slots 31. Bolts 32 extending through the slots 31 secure the plates to the wall of the drum, and packing in the groove 33 serves to make a tight joint between the plate and drum. The slots 31 permit the plates to be moved longitudinally of the drum in order to clamp them against the ends of the baffles. This clamping action is secured by the use of bolts 34 (Figs. 1 and 2) extending through the perforations 29 and the perforations 35 (Fig. 11) in the hangers. In this manner, the one set of bolts 34 serve to secure both closure plates tightly against the ends of the baffles. These plates are also preferably of cast iron.

What I claim is:

1. The combination with a steam drum, of a pair of hangers extending longitudinally of the drum on the opposite sides of the steam outlet and secured to the walls of the drum, a series of baffle plates carried by the hangers, closure plates with curved upper edges at the ends of the baffle plates, and means for securing the curved portions of the plates against the wall of the drum so that the plates may be adjusted longitudinally thereof and other means for securing the sides of the plates against the ends of the baffle plates.

2. The combination with a steam drum, of a pair of hangers extending longitudinally of the drum on opposite sides of the steam outlet and secured to the walls of the drum, a series of baffle plates carried by the hangers, closure plates with curved upper edges at the ends of the baffle plates, means for securing said curved edges against the wall of the drum for adjustment longitudi-

nally thereof, and other securing means extending entirely through the closure plates and the hangers for clamping the closure plates against the ends of the baffle plates.

3. The combination with a steam drum 70 having an outlet, of a baffle extending transversely beneath such outlet, and comprising a series of cast members or sections one above the other, means for supporting the top section from the drum, overlapping closure means at the sides and ends of the members integral with said members, and interengaging means between the successive members integral therewith whereby each one is suspended from the one next above it.

4. The combination with a steam drum having an outlet, of a baffle extending transversely beneath such outlet, and comprising a series of members or sections one above the other, means for supporting the top section from the drum, and interlocking slip connections between the successive members whereby each one is suspended from the one next above it, the parts of said connections being integral with the sections. 85

5. The combination with a steam drum having an outlet, of a baffle extending transversely beneath such outlet, and comprising a series of members, or sections one above the other, said sections each consisting of a plurality of inverted channels with their side walls spaced apart but connected at their lower edges by imperforate walls so as to provide longitudinal drain passages between the channels discharging into the drum at their ends, and said channels having their webs perforated to permit the passage of steam, the perforations in each baffle being out of vertical alinement with respect to the perforations in the baffle next above it. 90

6. The combination with a substantially horizontal steam drum, of a pair of hangers extending longitudinally of the drum, on opposite sides of the steam outlet and secured to the walls of the drum, a perforated distributing plate seated upon the hangers, and a series of baffle plates one above the other suspended from the distributing plate, each of said baffle plates having a series of parallel drain passages discharging at one end thereof, and each of said baffle plates having a series of vertical steam passages extending therethrough between the drain passages. 110

7. The combination with a substantially horizontal steam drum, of a pair of hangers extending longitudinally of the drum on opposite sides of the steam outlet and secured to the walls of the drum, a perforated distributing plate seated upon the hangers, and a series of baffle plates one above the other suspended from the distributing plate, each of said baffle plates having a series of parallel drain passages discharging at one end thereof, and each of said baffle plates 125

- having a series of vertical steam passages extending therethrough between the drain passages, the steam passages of each baffle plate being staggered with respect to those of the baffle plate above it.
8. The combination with a substantially horizontal steam drum, of a pair of hangers extending longitudinally of the drum, on opposite sides of the steam outlet and secured 10 to the walls of the drum, a perforated distributing plate seated upon the hangers, and a series of baffle plates one above the other suspended from the distributing plate, each of said baffle plates having a series of parallel drain passages discharging at one end thereof, and each of said baffle plates having a series of vertical steam passages extending therethrough between the drain passages, said hangers being formed so as to act as 15 side closures for the chamber lying above the distributing plate.

9. The combination with a substantially horizontal steam drum, of a pair of hangers extending longitudinally of the drum on opposite sides of the steam outlet and secured 25 to the walls of the drum, a perforated distributing plate seated upon the hangers, and a series of baffle plates one above the other suspended from the distributing plate, each of said baffle plates having a series of 30 parallel drain passages discharging at one end thereof, and each of said baffle plates having a series of vertical steam passages extending therethrough between the drain passages, and one of said hangers being extended down along the ends of the baffles to act as a splash shield for the ends of said channels.

In testimony whereof, I have hereunto subscribed my name this 25th day of June, 40 1927.

ALFRED C. DANKS.
